STEAM GENERATOR

Paul W. Goggins, P.O. Box 936,
Thomasville, Ga. 31792
Filed Oct. 2, 1964, Ser. No. 401,032
8 Claims. (Cl. 122—156)

This invention relates to apparatus for heating water and producing steam, and more particularly, it is directed to a steam generator which is fired by a gas or oil burner and which circulates hot combustion gases to heat water by both conduction and convection of heat from the combustion gases.

The boilers and steam generators of the type contemplated by this invention are necessarily heavy and bulky because of the strong construction required to accommodate high temperatures and pressures which are to be produced within the apparatus. These characteristics of weight and size often make it difficult to transport and install such devices, and the weight and size problem is especially pronounced in the case of heavy duty industrial type steam generators.

As an example of the difficulties that may be encountered, the space limitations within a boiler room itself, or in the passageways leading to the boiler room, may make it impossible to carry in a fully assembled boiler unit without making structural changes in the building itself, and once installed there is no provision for adjusting the position of the burner unit as related to the remainder of the unit. Usually, the positioning of the exhaust vent and pipe fittings is determined by pre-existing service facilities at the boiler room location, but once these elements are positioned, there is no way to adjust the position of the protruding burner unit relative to the remainder of the unit. Therefore, it can be seen that it would be desirable to provide for a relative adjustment of parts of the unit after it is installed in order to accommodate the unit to space restrictions of a given boiler room site.

I have provided a construction of a boiler or steam generator which is made up of two basic components, a combustion unit and a boiler unit, which may be rotated relative to one another in order that the assembled boiler or steam generator may be more readily adapted and adjusted to existing boiler room space conditions. This feature of adjustment allows the burner firing unit to be positioned in any of several positions, as required.

I have provided a construction which allows for the disassembly of the entire apparatus into the two basic units so that the apparatus may be more easily transported and handled prior to its installation at the site where it is to be used. By breaking the entire apparatus down into two basic components, it is possible to move the components through doorways and other limited access areas which otherwise could not be easily negotiated by the completely assembled unit. It is an important feature of this invention that the assembly, disassembly and relative adjustment of the components of the boiler or steam generator can be accomplished easily without affecting or otherwise upsetting the basic design of the apparatus.

In the operation of the boiler or steam generator, it is necessary to provide for a transfer of heat from hot combustion gases into water which is to be heated, and this transfer of heat is commonly effected by passing the hot gases through tubes or coils which are dispersed through the water jacket of the boiler. These gases normally make only a single sweep through the tubes or coils before they are exhausted to the atmosphere and it is therefore necessary to transfer as much heat as pos-

2

sible in this single sweep in order to avoid substantial heat losses. This is usually accomplished by constructing the tubes of relatively thin material to permit rapid conduction of heat, but of course, this results in a relatively short life for the boiler or steam generator because the tubes eventually burn out from sustained use at high temperatures.

Therefore, my invention involves a vertically firing boiler or steam generator which is so constructed that the hot combustion gases make three complete passes against the opposed surfaces of the boiler water jacket, thus creating a heat pattern within the water and allowing more of the combustion heat to be efficiently transferred to the water. Furthermore, by creating a heat pattern within the water, a circulation pattern of the water is established which results in quicker heat transfer throughout the boiler. The flow of the combustion gases and the conduction of heat are controlled by the use of heat control fins which will be described more completely in a later discussion. By eliminating tubes and coils from the water jacket construction, this invention provides for an apparatus which may be constructed of stronger material and which is less susceptible to burning out. Thus, a longer life of the entire unit is assured.

Prior tube-type boilers and steam generators have further disadvantages in that they are costly to manufacture, and difficult to clean and repair. Periodic cleaning or flushing is necessary because of the sediment or "mud" which accumulates in the lower part of the water jacket, and this mud often becomes hardened and even baked onto the walls of the water jacket, making it difficult to be removed by a simple flushing or washing action.

This invention provides for a boiler or steam generator which is so designed and constructed that it can be easily and economically constructed, maintained and cleaned. Inspection plates are provided which are easily removed and replaced, and access ports are included in the design to permit flushing and cleaning of mud and sediment from the bottom portion of the water jacket.

Also, this invention provides for a mud ring portion of the water jacket which is insulated from the heat of the combustion gases. This separate mud ring construction allows mud and sediment to accumulate in a portion of the water jacket which is relatively cool and which prevents the mud from hardening and baking onto the walls of the jacket. By keeping the sediment in a soft, unhardened state, it is a comparatively simple and economical operation to flush the sediment from the unit during periodic cleanings.

These and other features of this invention will become apparent in the more detailed discussion which follows.

Although this invention lends itself to various possible constructions and embodiments, it will be discussed in detail with particular reference to the preferred embodiment of a steam generator as illustrated in the accompanying drawings in which:

FIGURE 1 is a perspective view of the assembled steam generator showing the externally attached water and steam fittings, gauges and control devices which are not a part of the present invention;

FIGURE 2 is a perspective view of the assembled steam generator with sections cut away to show detail of the generator and to show the path of flow for hot combustion gases through the generator;

FIGURE 3 is a perspective view of the steam generator with the outer insulating shell removed to show detail of heat control fires, and with the upper boiler unit spaced from the lower combustion unit;

FIGURE 4 is a detail perspective view of one of the support brackets which join the lower combustion unit to the upper pressure unit;

FIGURES 5 through 7 are sectional top views of the steam generator to show three possible relationships between the two basic units of the steam generator;

FIGURE 8 is a sectional side view of the assembled steam generator;

FIGURE 9 is a top view of the supporting structure associated with the end plates; and

FIGURE 10 is an enlarged sectional side view of upper and lower end plates which are a part of the upper boiler unit. This view is taken at 10—10 of FIGURE 9.

As shown in FIGURES 1-3 and 8, the steam generator of this invention is made up of two basic units, a combustion unit 10 and a pressure unit 12.

The combustion unit 10 is made up of any suitable ceramic material 14 having an outer steel shell 16 and this unit serves as a base for the assembled steam generator. The combustion unit is provided with an inlet 18 which connects an externally attached gas or oil burner 20 to an internal combustion chamber 22. The gas or oil burner 20 may be of any suitable electrically driven forced draft type of burner which delivers fuel to the combustion chamber 22 where it is ignited and burned. The combustion chamber 22 is generally cylindrical in shape but is constructed with inwardly tapered walls 24 near the top of the chamber so that heat will be reflected and concentrated back into the central part of the chamber, thereby providing a better ignition of and a more complete burning of gases in the combustion chamber. An uppermost extension 26 of the combustion unit 10 provides for a communication between the lower combustion unit 10 and the upper pressure unit so that hot combustion gases can pass into a central firing tube 28 which is a part of the upper pressure unit 12. This extension 26 is defined by an upwardly extending wall portion 29 of insulating material which extends from the upper face 30 of the combustion unit 10. The extension 26 serves to insulate a portion of the lower water jacket for a purpose which will be discussed in greater detail later. Additionally, the extension 26 serves as an aligning means for assisting in the alignment of the combustion unit with the pressure unit when the steam generator is being assembled or rotated.

The pressure unit 12 is removably mounted on the combustion unit 10, and this may be accomplished with any suitable mounting means such as support braces 31 which provide for an easy assembly and disassembly of the two basic units 10 and 12.

With reference to FIGURES 2-4, it can be seen that the four support braces 31 are equally spaced around the lower perimeter of a water jacket 32, which is a part of the upper pressure unit 12. The support braces 31 include base portions 34 and upright wall portions 36 which are rigidly secured to each other at right angles and which are reinforced by means of the upright bracing walls 38. These support braces are permanently affixed to an outside wall portion 40 of the water jacket 32, such as by welding the upright wall portion 36 of the support brace to the outside wall portion 40 of the water jacket. When properly affixed, the support braces 31 will be equally spaced from one another around the lower periphery of the water jacket, and the base portions 34 of the support braces will project outwardly from the central longitudinal axis of the upper pressure unit 12.

The support brace 31 is also provided with a bore 42 through the base portion 34 and this bore is adapted to receive a threaded stud or bolt 44 which may be used to removably secure the upper pressure unit 12 to the lower combustion unit 10. Suitable bores are provided on the upper face portion 30 of the lower combustion unit 10 for receiving the studs 44, and these bores of the combustion unit 10 are positioned to line up with the bores 42 of the support braces 31 when the upper pressure unit 12 is placed on the lower combustion unit 10. The studs or bolts 44 may be threaded into the lower combustion unit or otherwise affixed so as to leave a threaded end exposed in order that nuts may be used to attach the upper pres-

sure unit to the lower combustion unit. In this manner, the threaded studs 44 may be permanently affixed in position within the bores 42 of the combustion unit and the upper pressure unit 12 may then be lowered into position 5 with the support braces properly aligned for mating assembly with the studs 44. From that position, the two basic units may be tightly secured by turning nuts 48 (FIGURE 1) downwardly onto the threaded ends of the studs 44 until a tight coupling of the two units is accomplished.

It can be appreciated that this means of coupling provides for a steam generator unit which can be easily disassembled for transporting or for carrying through confined spaces to a boiler room site. It can be further appreciated that it is a comparatively simple and easy task 10 to reassemble the two basic units into a complete unit without affecting the design or function of the unit.

It is also a feature of this invention to provide for an 15 adjustment of the lower combustion unit 10 relative to the upper pressure unit 12 once the steam generator is located at the boiler room site where it is to be used. The desirability of this feature becomes obvious when it is realized that the upper pressure unit part of the steam generator carries with it all fittings for service connections 20 to exhaust vents, water inlets and outlets, steam outlets and other necessary connections to make the steam generator operational. In accordance with this invention, the upper part of the steam generator is positioned to most effectively provide for a connection of these service connections 25 to existing facilities, and the lower combustion unit portion of the steam generator is then rotated to a position where the protruding burner 20 is best fitted to the space requirements of the particular site. With the use of four support braces as described above, the base 30 unit may be rotated 90° at a time, thus providing four possible positions for the protruding burner as related to a given position of the upper pressure unit. Three possible positions are shown in FIGURES 5-7 where the burner position 22 is rotated with respect to an exhaust vent 49.

40 Of course, it is contemplated that the addition of more support braces with an equal addition of mating positions on the base unit would provide for increments of adjustment of less than 90°, if such finer adjustment should be required.

45 Turning now to the specific construction of the pressure unit as illustrated in FIGURES 2, 3 and 8, it can be seen that the pressure unit 12 includes a water jacket 32, a water and steam reservoir 50 which is an extension of the water jacket, heat flow control fins 52, and service connections (not shown) for a water inlet, a steam outlet and an exhaust 49 for combustion products. The water jacket and heat exchange portions of the pressure unit are enclosed within a cylindrical insulating shell 54 which is cast from any suitable insulation material 55 and this shell is 50 covered with a steel jacket 56.

55 The water jacket 32, and the steam and water reservoir 50 together form the boiler 58 of the steam generator of this invention. The water jacket portion and the reservoir portion are essentially integral and provide for a ready circulation of water throughout the entire boiler. The boiler 58 contains the water to be heated together with steam produced from the water, and of course, the boiler is constructed from material which can withstand the temperatures and pressures developed within a typical steam generator. Pipe means are provided for conducting water 60 into the boiler and for carrying steam out for ultimate consumption, but these pipes and other necessary control devices are not a part of this invention and will be understood by those skilled in the art to be associated with this invention.

65 With particular reference to FIGURE 8, the water jacket 32 has an inner wall 62 and an outer wall 40. The inner wall 62 defines the central firing tube 28 and is in direct contact with the hot combustion gases rising from the combustion chamber 22. The outer wall 40 defines the 70 outer periphery of the water jacket 32.

outer perimeter of the entire boiler 58. The bottom plate 64 of the water and steam reservoir forms a closed end wall to the central firing tube 28, and thus the hot combustion gases are prevented from making a single straight-through sweep in their passage from the combustion chamber 22 to where they are exhausted to the atmosphere. An end wall 65 at the bottom of the water jacket defines the bottom end of the boiler 58, and a top wall 67 of the reservoir forms the top end of the boiler.

The water jacket 32 is further provided with a plurality of access ports 66 through the outer wall 40, and these access ports are for purposes of inspecting and cleaning the interior of the water jacket. Similar access ports 68 are provided in the wall 70 of the water and steam reservoir 50 in order that the reservoir may also be conveniently inspected or cleaned. Of course, the access ports 66 and 68 are provided with closures and are kept closed during operation of the steam generator. The closure means may be any suitable means for providing a tight seal against the high temperatures and pressures generated by the boiler unit.

As shown in FIGURES 2 and 3, the boiler 58 is provided with four openings 60 which are arranged at 90 degrees from one another at the uppermost portion of the water jacket 32. The openings 60 serve as exits for hot combustion gases from the central firing tube 28 in order that these gases may be caused to make a series of passes through the steam generator, as will be described more fully later. It will be appreciated that the openings 60 must be completely sealed from the water zone within the water jacket since the hot combustion gases never directly contact the water to be heated in a steam generator of this type. Such a sealing is accomplished by the wall portions 61 which span the space between the inner and outer walls of the water jacket. The wall portions 61 form a conduit through the water jacket through which the hot gases may pass. Of course, it is contemplated that a greater or lesser number of openings may be utilized than the four shown in the preferred embodiment. The outer wall 40 of the water jacket is provided with heat control fins 52 which serve to control the convective flow of hot gases over the outer surface of the boiler, and which also serve to conduct heat from the hot gases into the water within the water jacket. The fins 52 are of several lengths as shown in FIGURE 3 and are permanently affixed to the outer wall 40 of the water jacket, as by welding.

All of the fins terminate at a common level at their lower ends and this lower termination is at a point which is well above the lowermost level of the water jacket itself. The upper ends of the fins terminate at varying levels depending upon the particular function and location of the individual fins.

Looking to FIGURE 3, the shortest length fins 72 extend longitudinally along the outer wall 40 of the water jacket from points even with the lower edges of the openings 60 down to the common lower terminus of all fins, indicated at 73. These shortest length fins 72 are shown as being arranged in groups of five and these groups are located at spaced intervals below each of the openings 60. Each separate group covers a width of the outer wall surface 40 which is approximately equal to the width of one of the openings 60. Thus, there is provided a path for hot combustion gases which are exiting from the openings 60 to travel downwardly along the outside surface of the water jacket along equally spaced sections of the wall as defined by the fins 72. The hot combustion gases are deflected downwardly upon leaving the openings 60 by any suitable deflection means associated with the openings 60. Such deflection means have been shown as baffles 69 which are located above the openings 60 and which prevent the hot gases from rising when they exit from the openings. The intermediate length fins 74, which are also arranged in groups of five, provide a controlled-width path for a final pass of the hot gases upwardly along the outer surface

of the boiled. The spaced locations of the groups of fins 74 alternate with the spaced locations of the groups of fins 72 as shown in FIGURE 3. The fins 74 are longer in length than the fins 72 so that heat may be conducted throughout their entire length into the water jacket 32. The upper terminating points of the fins 74 are approximately even with the level where the reservoir 50 adjoins the water jacket 32, and the lower terminus of the fins 74 is common with all of the fins at 73.

The longest fins 76 are arranged singly between the groups of fins 72 and 74 so as to maintain a separation of the downwardly flowing hot gases in the paths defined by the groups of fins 72 from the upwardly flowing gases in the paths defined by the groups of fins 74. The fins 76 extend longitudinally up along the lower part of the reservoir 50, however, they do not cover the entire length of the reservoir because it is essential that the gases, upon reaching the top of the boiler after their final sweep past fins 74, will be free to travel around the outer circumference of the boiler wall 70 to an exhaust vent 49, shown as a dotted circle in FIGURE 8.

It is a feature of this invention that the flow paths for the hot combustion gases are so arranged that a scrubbing or cleaning action takes place by the action of the hot gases moving through the steam generator in the series of passes described above. The scrubbing action is accomplished by decreasing the size of each subsequent path as the gases move from the central firing tube to their ultimate exhaustion to the atmosphere. Thus, it will be appreciated that the volume of space in the combined downward flow paths defined by the groups of fins 72 is less than the volume of space in the central firing tube. Likewise the volume of space in the combined upward flow paths defined by the groups of fins 74 is less than the volume of space in the paths of fins 72. By this arrangement, the velocity of the gases is increased as the gases pass back and forth through the steam generator, and as a result there is a cleaning action which helps prevent a buildup of carbon deposits on the walls of the boiler.

The final element of the assembled pressure unit 12 comprises an insulating shell 54 which extends around the boiler unit from the top of the water and steam reservoir 50 down to a level which stops above the lowermost portion 80 of the water jacket. The portion 80 of the water jacket will hereinafter be termed the mud ring since it is that part of the water jacket where sludge and sediment settle out from the water which is being heated. It is apparent that the insulating shell 54 contacts and cooperates with the fins 52 of the water jacket to hold as much heat as possible within the heat conductive zones of the boiler unit thereby assuring a greater efficiency in transferring heat from the hot combustion gases into the water which is being heated to generate steam. The insulating shell 54 has an outer steel jacket 56 and an inner insulating layer 55 cast from any suitable insulation material. It can be seen that the inner insulating layer 55 extends for the entire length of the insulating shell 54. However, the thickness of the insulation layer 55 is less at the top portion 82 which surrounds the water and steam reservoir 50 than it is in the lower portion 84 which surrounds the water jacket and its associated fins.

The top portion 82 of the insulation material is thinner than at the remainder of the insulating shell because the combustion gases at this level are ready to be exhausted to the atmosphere and are much cooler than the initial temperature in the central firing tube; therefore there is less reason to retain heat in this area of the generator. An additional reason for the thinner wall of insulation at 82 resides in the necessity for providing a space 86 for the circumferential movement of the combustion gases around the reservoir 50 and out of the exhaust vent 49.

The lower portion 84 of the insulation material of the shell 54 is thicker than the portion 82 to provide greater

efficiency in retaining heat against the heat conductive portions of the water jacket 32. Also, it can be seen that the thickness of insulation in the portion 84 must be sufficient to effectively prevent any circumferential movement of gases around the water jacket 32 in the region of the fins 52. By contacting the outer edges of the fins 52 with the insulation layer 84, there is provided an effective seal between the fins and the insulation layer, and the insulation layer 84 then serves to cooperate with the fins 52 to confine the flow of gases over the outside surface of the water jacket.

The insulation layer 84 extends downwardly along the longitudinal axis of the water jacket to a point which is beyond the lower terminus of the fins 52 in order to provide a space 88 for gases to turn from their downward flow and to begin their upward flow along an adjacent group of fins. However, it is important that the insulation layer not extend over the region of the water jacket which is termed the mud ring 80 because the mud ring is purposely insulated from heat as much as possible in order to prevent sludge and sediment from hardening and baking onto the interior walls of the water jacket, as is common in prior generators of this type.

The insulating shell 54 is further provided with upper end plates 90 and lower end plates 92 which serve to form end walls for spaces 86 and 88 respectively. These end plates 90 and 92 are arranged in segments around the top and bottom ends of the insulating shell 54 and are easily removable to provide for inspection of the spaces between the boiler unit and the insulating shell. In addition to serving as removable inspection plates, the end plates 90 and 92 also act as baffles at opposite ends of the gaseous flow paths and serve to turn the flow of gases when gases strike them.

The attachment of the end plates 90 and 92 to supporting structures can be seen in greater detail in FIGURES 9 and 10. In FIGURE 9, the supporting structure 93 for the top end plate 90 is shown in a top view as having an inner band 94 and an outer band 96 spaced from the inner band. The inner band 94 is of such a size as to be affixed around the top of the reservoir section 50 of the boiler. The outer band 96 is attached to the steel jacket 56 of the insulating shell 54, and bracket members 98 are interposed at spaced points between the inner and outer bands 94 and 96 as shown in the view in FIGURE 9.

The inner band 94 is provided with means 100 for tightening the band once the supporting structure 93 is positioned around the boiler unit. The tightening means 100 may be any suitable screw device, or the like for drawing together the ends 102 and 104 of the inner band 94. It will be appreciated that prior to tightening the band 94 a sufficient gap 106 exists between the ends 102 and 104 of the inner band to allow a final tightening of the band around the boiler unit.

A similar supporting structure is provided for the bottom end plates and the relative positions of the top and bottom supporting structures is illustrated in FIGURE 10 taken at 10-10 of FIGURE 9. When in position around the boiler unit, the supporting structures provide means 108 for removably attaching the top and bottom end plates in their proper positions against the top and bottom perimeter respectively of the insulating shell 54. Attaching means 108 may be threaded studs or bolts adapted to receive nuts 110, and a stud 108 is associated with each bracket member 98. Thus, end plate segments (as illustrated by top plate segment 90, FIGURE 9) may be threaded across bracket members 98, and when removed the spaces 89 and 88 between the boiler unit and the insulating shell may be readily inspected and/or cleaned. In the preferred embodiment of this invention, an insulating layer 112 is placed between the supporting members 93 and the attached end plates in order to provide for better retention of heat within the steam generator. The insulating layer 112 may be made

in segments to correspond to the end plate segments, thus providing for a ready removal of both the end plate segment and its associated insulating layer segment 112.

Having described the details of construction of the steam generator, the operation of the generator may now be discussed.

Initially, the unit is installed and adjusted, as described above, to provide the desired relationship between the positions of the combustion unit 10 and the pressure unit 12. After the steam generator is fully installed and operational, hot combustion gases are produced by the firing of fuel delivered by the burner unit 20 into combustion chamber 22. The hot gases rise upwardly through the central firing tube 28, and in this first pass through the length of the boiler unit, heat is conducted through the inner wall 62 of the water jacket 32 into the water which is to be heated. When the hot gases reach the uppermost point of the central firing tube, they are deflected outwardly by the wall 64 of the water and steam reservoir. It will be appreciated that the reservoir wall 64 forms an end wall to the central firing tube 28, and as the hot gases strike the end wall in their upward pass through the boiler unit, heat is transferred directly into the water in the reservoir. Thus, in the first pass through the steam generator, heat from the hot combustion gases is given up to water in the water jacket portion of the boiler and to water in the reservoir portion of the boiler as well. It should be noted at this point, that during the initial pass through the steam generator all of the hot gases are completely surrounded by water. The gases are at their hottest temperature during this first pass, and it is safer and more efficient in a steam generator to surround these hottest gases as much as possible with water jacket portions.

Since the reservoir wall 64 forms an end wall to the central firing tube, the hot combustion gases are deflected outwardly through the plurality of openings 60 situated through the uppermost section of the water jacket 32. Upon exiting outwardly from the openings 60, the hot combustion gases are now deflected downwardly along the outside wall of the water jacket 32. The baffle structure 69 spaced around the outer wall 70 of the reservoir 50 at intervals above each of the openings 60, prevents the hot combustion gases from rising as they are deflected outwardly from the openings 60. Thus, the downward deflection of the gases at spaced intervals around the outside wall of the water jacket is assured, as shown by the flow arrows in FIGURES 2, 3 and 8.

The hot gases flow downwardly in this second pass through the steam generator along paths defined by the shortest heat control fins 72. As described earlier, the heat control fins serve to conduct heat into the interior of the water jacket. In addition, the fins cooperate with the insulating shell 54 to control the convective flow of the hot gases along the length of the outside wall of the water jacket. Since the outside edges of the heat control fins contact the inside wall of the insulating shell 54, an effective seal is formed, and it is impossible for the hot gases to flow transversely around the perimeter of the boiler in the region of the fins. In this manner the flow of gases can be controlled to make a series of longitudinal passes along a major part of the boiler, and greater heat conduction and efficiency of operation are accomplished.

The downward flow of hot gases takes place at spaced intervals around the outside wall of the water jacket as determined by the groups of fins 72 which are grouped below the spaced openings 60. Upon reaching the lower terminus 73 of the fins 72, the gases continue downwardly into the space 88 until they strike the lower end wall formed by lower end plates 92 and their associated insulation segments 112. The lower end plates act to seal the hot gases within the steam generator unit, and the gases are therefore deflected transversely around the lower outside wall of the water jacket.

The hot gases are prevented from returning up the path defined by the control fins 72 because the pressure of additional hot gases coming downwardly along that path continually forces the gases along in their movement through the steam generator. Also, the transverse deflection of the hot gases around the lower space 88 is limited by the presence of other gases having completed their downward passes along the downward paths defined by the fins 72 under each of the four openings 60. Therefore, the gases from all of the downward passes turn upwardly along the paths which alternate with the downward pass paths. These upward paths are located at spaced intervals defined by the groups of intermediate length fins 74, and it is along these paths that the hot gases make a third and final pass, along the major length of the outside water jacket wall. The third pass conducts additional heat to the water in the water jacket, providing a high degree of efficiency in obtaining heat from the hot combustion gases which originated in the combustion chamber 22.

In addition to the efficiency obtained by causing the hot gases to make three complete passes along the length of the water jacket, an additional advantage in this construction lies in the heat patterns which are formed in the water jacket. The three passes of hot gases against the water jacket are made at varying temperatures since the gases give up heat during each pass. Thus, there is formed a heat pattern in the water jacket which includes a balanced temperature in the central tube and with the outer wall being hot in sections and cooler in others. This creates circulating cycles of water movement, which are counterflow to the gas movements. The heat patterns established on the water jacket create a novel water circulation pattern which insures a higher rate of heat exchange and a greater efficiency in steam generation.

Another feature of the preferred constructions provides a scrubbing action of the gases in their passage throughout the steam generator. This scrubbing action results from the provision of narrower paths to be followed by the gases in each subsequent passage in the series of passages through the generator. It will be noted that the central firing tube is of a greater volume than the combined volumes of the four downward paths and likewise the combined volume capacity of the four downward paths is greater than the total volume of the four final upward paths. Thus, as the gases progress in their travel throughout the steam generator, pressure and velocity are increased, and this provides a scrubbing action which maintains the steam generator in a cleaner, more efficient operating condition at all times.

When the hot gases have completed their final upward pass, as described above, they enter the upper space 86 surrounding the reservoir 50, and they make their way transversely around the top of the reservoir 50 to the exhaust vent 49 provided for carrying gaseous combustion products to the atmosphere. It should be noted that even in this final pass around the reservoir prior to being exhausted, the gases may conduct additional heat into the boiler by conduction through the wall 70 of the reservoir.

It is desirable in steam generators of this type to be able to periodically inspect and clean the unit, as required. For that purpose, the removable top and bottom end plates 90 and 92, respectively, are provided for an inspection or cleaning of the spaces between the outer wall of the boiler 58 and the inner wall of the insulating shell 54. A detailed description of the end plates 90 and 92 was given above in the discussion of FIGURES 9 and 10.

Further access to the unit is provided by the hand holes or access ports 66 located in the lower water jacket section described as the mud ring 80, and these access ports 66 may be opened for cleaning of the mud ring section by flushing or by any other suitable method. As described above, the mud ring section 80 of the water jacket is substantially insulated from the hot combustion gases of the

generator, and therefore the sludge and sediment which settle into the mud ring section remain in a soft state and are more easily removed. The insulation of the mud ring inner wall is provided by the extending wall portion 29 5 of the lower combustion unit 10, and the outer wall of the mud ring is insulated by an absence of the heat-retaining insulating shell 54 in the region of the mud ring.

The access ports 68 have been described as located in the wall 70 of the water and steam reservoir 50, and these 10 ports provide for inspection and cleaning of the upper sections of the boiler unit 58. Also, it is possible to use the access ports 68 in cooperation with the lower ports 66 for back flushing scale and sediment from the entire boiler, including the mud ring.

15 The access ports 68 are normally not visible from the outside of the assembled unit, and are made accessible only by the removal of a panel element of the outer steel jacket 56, as at 120. The panel 120 of the outer jacket 56 may be mounted for easy removal by any suitable 20 means such as by spring clips or the like. FIGURE 1 shows two panels 120 in place, and a third one is removed to show one of the access ports 68 with its closure in place.

Having described the construction and operation of the 25 steam generator of this invention, it can be seen that the objects of this invention have been fully met. It is contemplated that variations of the above described preferred embodiment will become obvious to those skilled in the art, and such variations may be made without departing 30 from the scope of this invention.

I claim:

1. A steam generator comprising a combustion unit for burning fuel and a boiler unit for heating water from the heat of said burning fuel, said boiler unit including a 35 water jacket portion for holding water to be heated by conduction and a reservoir portion for storing heated water and steam, said water jacket portion and said reservoir portion being in communication with one another for circulation of water between the two portions; said water jacket portion comprising an inner wall and an outer wall, said inner wall forming a firing tube in open communication with said combustion chamber so that hot combustion gases may pass from the combustion chamber unit into the water jacket portion of the boiler unit; an 40 end wall in said water jacket portion common to the reservoir portion and forming a closed end to the central firing tube whereby said central firing tube is completely surrounded by water retaining walls; a plurality of radial discharge openings through said water jacket portion located near the closed end of said central firing tube thereby providing exits for hot combustion gases which have been deflected by the closed end wall of said central firing tube after completing a first pass through said boiler unit, deflection means associated with said outer wall of said 45 water jacket portion for turning the hot combustion gases as they exit from said radial discharge openings whereby said gases are caused to make a second pass through said boiler unit through a first plurality of spaced paths extending substantially the entire length along said water jacket portion outer wall, additional deflection means associated with said outer wall of said water jacket portion for turning said gases upon completion of the second pass through said boiler unit whereby said gases are caused to 50 make a third pass through the boiler unit along a second plurality of spaced paths on said water jacket portion outer wall, said second plurality of spaced paths being alternated with said first plurality of spaced paths so that a counter-flow of hot gases is established between adjoining paths; heat control means associated with said outer wall of said water jacket for promoting a more rapid conduction of heat into the water to be heated and for directing the flow of hot gases along the outside wall paths of said water jacket; and insulating means cooperating with 55 said deflection means and said heat control means for confining heat to selected portions of said boiler unit

whereby a heat pattern is established in the water jacket portion of said boiler unit.

2. A steam generator according to claim 1 where said heat control means comprise heat-conductive fin elements attached longitudinally to the outer wall of the water jacket.

3. A steam generator according to claim 1 where said water jacket portion further includes a mud ring portion for receiving scale and sediment settling out from the water which is being heated, and an insulation barrier for maintaining the mud ring portion of the boiler unit at a cooler temperature than the remainder of the water jacket portion, whereby scale and sediment settling in said mud ring portion will remain in a soft, unbaked state for easy removal from the water jacket.

4. A steam generator according to claim 3 where said insulation barrier comprises an extension portion of material from said combustion unit, said extension portion being interposed between the burning fuel and the mud ring portion of said water jacket portion.

5. A sectional steam generator comprising a combustion unit for burning fuel and a boiler unit for heating water from the heat of said burning fuel, attachment means for removably securing the combustion unit to the boiler unit so that the two units may be easily assembled, disassembled and rotated relative to each other; said boiler unit including a water jacket portion for holding water to be heated by conduction, and a reservoir portion for storing heated water and steam, said water jacket portion and said reservoir portion being in communication with one another for circulation of water between the two portions; said water jacket portion comprising an inner wall and an outer wall, said inner wall forming a firing tube in open communication with said combustion chamber so that hot combustion gases may pass from the combustion chamber unit into the firing tube of the water jacket portion; an end wall in said water jacket portion common to the reservoir portion and forming a closed end to the central firing tube whereby said central firing tube is completely surrounded by water retaining walls; a plurality of radial discharge openings through said water jacket located near the closed end of said central firing tube and providing exits for hot combustion gases which have been deflected by the closed end wall of said central firing tube after completing a first pass through said boiler unit, deflection means associated with said outer wall of said water jacket for turning the hot combustion gases as they exit from said discharge openings whereby said gases are caused to make a second pass through said boiler unit along substantially the entire length of a first plu-

rality of spaced paths on said water jacket outer wall, addition deflection means associated with said outer wall of said water jacket for turning said gases upon completion of the second pass through said boiler unit whereby said gases are caused to make a third pass through the boiler unit along a second plurality of spaced paths on said water jacket outer wall; said second plurality of spaced paths being alternated with said first plurality of spaced paths so that a counter-flow of hot gases is established between adjoining paths, heat control means associated with said outer wall of said water jacket for promoting a more rapid conduction of heat into the water to be heated and for directing the flow of hot gases along the outside wall paths of said water jacket, and insulating means cooperating with said deflection means and said heat control means for confining heat to selected portions of said boiler unit whereby a heat pattern is established in the water jacket portion of said boiler unit.

6. A sectional steam generator according to claim 5 where said heat control means comprise heat-conductive fin elements attached longitudinally to the outer wall of the water jacket portion.

7. A sectional steam generator according to claim 5 where said water jacket portion further includes a mud ring for receiving scale and sediment settling out from the water which is being heated and an insulation barrier for maintaining the mud ring of the water jacket portion at a cooler temperature than the remainder of the water jacket portion, whereby scale and sediment settling in said mud ring portion will remain in a soft, unbaked state for easy removal from the water jacket.

8. A sectional steam generator according to claim 7 where said insulation barrier comprises an extension portion of material from said combustion unit, said extension portion being interposed between the burning fuel and the mud ring portion of said water jacket.
